UNITED STATES PATENT OFFICE.

ALEXANDER KELLEY, OF WILMINGTON, DELAWARE, ASSIGNOR OF ONE-HALF TO ANTHONY HIGGINS, OF WILMINGTON, DELAWARE.

MATCH-MAKING MACHINE.

No. 806,813.

Specification of Letters Patent.

Patented Dec. 12, 1905.

Application filed November 25, 1902. Renewed May 13, 1905. Serial No. 260,333.

To all whom it may concern:

Be it known that I, ALEXANDER KELLEY, a citizen of the United States, residing in Wilmington, in the county of Newcastle and State 5 of Delaware, have invented certain new and useful Improvements in Match-Making Machines, of which the following is a true and exact description, reference being had to the accompanying drawings, which form a part 10 thereof.

My invention relates to machinery for making matches, and has for its object to provide a match-making-machine carrier of high efficiency and great simplicity of construction.

15 The leading feature of my invention consists in the provision of a carrier-belt provided with spring-grippers adapted to receive and hold the match-sticks during the operation of converting them into matches and in coaction 20 with other devices acting on the spring-grippers to disengage the completed matches at a determined point in the travel of the carrier-belt.

Other features of my invention will be best 25 understood as described in connection with the drawings, in which my invention is illustrated, and in which—

Figure 1 is a side elevation of a machine provided with my invention. Fig. 2 is a perspective view of a portion of the carrier-belt, 30 showing the spring stick-holders and the rods by which they are opened to disengage the matches. Fig. 3 is a side elevation showing a portion of the carrier-belt with attached 35 holders and the cam-plate by which the holders are opened to disengage the matches. Fig. 4 is a view showing a portion of the carrier-belt with attached holders and the fingers which in the construction illustrated I employ 40 to insure that the holders shall be in proper position and condition to receive the match-sticks.

A indicates the carrier-belt, which, as shown, 45 consists of two sprocket-chains A' A', running over conveniently-placed sprocket-wheels, the links of the sprocket-chains being connected in pairs by the spring-holders, which, as best shown in Fig. 2, have outwardly-extending ends A² A², which are riveted to the links of 50 the chain, the central part of the holders consisting of what I may call a "U-shaped" spring, (indicated at A³), the bent arms of the spring tending by their elasticity to approach each other and being at their ends flared out-

ward, as indicated at A⁴ A⁴, these arms being 55 preferably also provided with notches (indicated at a⁴ a⁴) pressed into the material and forming seats or sockets adapted to receive the match-sticks. I provide, in connection with the spring-holders, means for distending 60 the spring-arms, which, by preference, I construct as cam-like rods B B, &c., one contained in each socket or base of the U-shaped spring-holder, the said rods being formed eccentric or with a projection, as indicated at B', so that 65 when turned in the spring-socket the eccentric or projecting portions will press against the sides of the spring-holder and force the sides apart, so as to release their grip upon the match-sticks. The rods B are provided 70 with crank-arms B², which, by preference, turn outward at the end, as indicated at B³.

C C' C², &c., indicate sprocket-wheels over which the chains of the carrier pass and which may be distributed in any convenient manner. 75 All or only some of these sprocket-wheels may be driven by power, and, as shown in Fig. 1, I have represented only the sprocket-wheels C⁶ C⁸ as so driven, though in actual construction it will be found convenient to couple 80 others of the sprocket-wheels to the power driving mechanism, the position and number of the wheels to be so positively driven depending on the organization of the system as a whole. 85

D is the power-shaft of the machine, which may be driven by a belt coupled, for instance, to the pulley (indicated at D⁴) or in any other convenient manner. The shaft D is, as shown, supported on arms of the frame, (indicated at 9c I.) Through a gear-wheel it communicates motion to a bevel-gear (indicated at E) secured on the base of a shaft E', having at its upper end a worm E², (see Fig. 1,) which engages and drives the worm-wheel E³, secured 95 on the same shaft as the sprocket-wheel C⁶, these sprocket-wheels in the construction shown being driving-wheels which propel the carrier-belt. Another bevel-wheel drives, through the bevel F, the shaft F', which has 100 secured to its other end the intermittently-acting worm, (indicated at F²), which engages and drives the worm-wheel F³, secured to the shaft which carries the sprocket-wheels C⁶ C⁸. The construction of the intermittently-acting 105 worm F² is such that at each revolution of the shaft D it drives the sprocket-wheels C⁶ through the same linear distance traveled by

a point on the sprocket-wheels C^6 ; but the motion thus imparted to the sprocket-wheel C^8 is intermittent, the said sprocket-wheels and the portion of the carrier directly supported thereon remaining stationary for a period sufficient to enable the match-sticks to be fed to the holder in registry with the feed apparatus to be described and the motion imparted to the carrier-wheels C^8 being in each case just sufficient to bring the successive carriers in turn into registry with the feed apparatus. The shaft D communicates motion through connecting-rods H H to a sliding head H' , moving in guideways I' I' of the frame I , said sliding head carrying a series of plungers, (indicated at H^2 H^2 , &c.). The shaft D also communicates motion, through an eccentric-rod J , to a lever J' J^2 , pivoted to an upwardly-extending arm I^2 of the frame I at I^3 and having its arm J^2 (see Fig. 4) arranged to successively engage and operate upon the outwardly-extending ends B^3 of the crank-arms B^2 , extending from the rods B .

K^4 K^6 is a stick-receiving hopper, through a properly-formed bottom of which the plungers H^2 move, forcing out in front of them a series of sticks, which are thus fed to the stick-holders of the belt.

At M and N , I have indicated the paraffin and composition tanks.

P is a frame on which, as shown, are supported the shafts of the sprocket-wheels C^4 and C^6 . Said frame also supports the cam P' , (see Figs. 1 and 8,) which as the carrier-belt advances comes in contact with the outwardly-extending ends B^3 of the rods B , operating upon them, as shown in Fig. 3, so as to open the arms of the spring-holders and release their grip upon the matches.

P^2 is a receiving-belt upon which the matches fall from the carrier-holders, said belt passing over the pulley P^4 , secured to the shaft P^3 , which is actuated through a belt Q by the pulley D^6 on the shaft D . The shaft P^3 drives, through a belt P^6 and pulley P^6 , a shaft P^7 , having secured to it arms P^8 , which act intermittently against a lever-arm P^9 , secured to a shaft P^{10} , to which shaft is also secured the tapping-hammer, (indicated at P^{11}), and this hammer driven by the mechanism described tapping lightly on the rear of the holders as they pass it and after they have been bent, so as to insure that the matches will fall out of them onto the carrier-belt P^2 .

The operation of my machine is as follows: The carrier-belt is positively and regularly driven by the power-driven sprocket-wheels C^6 and any additional sprocket-wheels which it may be found best to connect with the power mechanism. In passing over the sprocket-wheels C^8 , however, the motion of the carrier-belt is intermittently checked, the stoppage of the motion of these sprocket-wheels bringing each holder in turn to a standstill in front of the hopper K^4 , and after the holder has been

charged with match-sticks the motion of the belt is resumed and the charged portion carried forward, carrying the ends of the sticks through the paraffin-tank M . The sticks are then carried over the composition-tank N , the ends of the sticks coming in contact with the composition roll, from which each stick takes up its head. The headed match-sticks are then carried by the carrier-belt through a sufficient distance to insure the setting and hardening of the heads, and then passing under the sprocket-wheels C^4 the cam-rods B are shifted by the cam-plate P' , as shown in Fig. 3, to release the matches from the holders, the tapping-hammer P^{11} insuring that all the matches will fall from the holders onto the belt P^2 .

The construction of the cam-rods B is preferably such that when released from the action of the cam-plate P' they will, under the influence of the spring sides of the holders, move back to normal position, permitting the arms of the holders to move together. In case, however, the cam-rods should become jammed or for other reason the arms of the holders fail to close together after releasing the matches it is advisable to provide mechanism which will act upon the crank-arms of the cam-rods B and restore them to normal position, and for this purpose I have provided the lever J' J^2 , already described, which, as shown in Fig. 4, will engage and push to normal position any of the cam-rods which may reach it in turned-back position.

Having now described my invention, what I claim as new, and desire to secure by Letters Patent, is—

1. In a match-making machine, a carrier-belt having a parallel series of **U**-shaped gripping-springs, A^3 , A^3 , &c., each adapted to engage and hold a series of match-sticks, in combination, with means for forcing the arms of said spring-holders apart to release the sticks.

2. In a match-making machine, a carrier-belt having a parallel series of **U**-shaped gripping-springs, A^3 , A^3 , &c., with arms, A^4 , flaring outward at their ends, each said spring adapted to engage and hold a series of match-sticks, in combination, with means for forcing the arms of said spring-holders apart to release the sticks.

3. In a match-making machine, a carrier-belt having a parallel series of **U**-shaped gripping-springs, A^3 , A^3 , &c., with arms A^4 flaring outward at their ends and formed with recesses, a^4 , a^4 , &c., each said spring adapted to engage and hold a series of match-sticks, in combination, with means for forcing the arms of said spring-holders apart to release the sticks.

4. In a match-making machine, a carrier-belt having a series of parallel **U**-shaped gripping-springs, A^3 , A^3 , &c., each adapted to engage and hold a row of match-sticks, in combination with a series of spring distending-bars B , B , &c., one lying in the hollow of each

spring and adapted when turned to open the arms of the springs, and means for turning said rods B, B, &c., located in the path of the belt.

5 5. In a match-making machine, a carrier-belt having a series of parallel U-shaped gripping-springs, A³, A³, &c., each adapted to engage and hold a row of match-sticks, in combination with a series of spring distending-bars, B, B, &c., one lying in the hollow of

each spring and adapted when turned to open the arms of the springs, means for turning said rods B, B, &c., located in the path of the belt, and means for tapping the springs, located in the path of the belt at a point where 15 the matches are delivered.
